UNITED STATES PATENT OFFICE.

JOHN D. RAYMOND, OF CHICAGO, ILLINOIS.

ELECTRIC-LIGHTING FIXTURE.

1,153,286.

Specification of Letters Patent. Patented Oct. 26, 1915.

Application filed June 12, 1915. Serial No. 33,632.

To all whom it may concern:

Be it known that I, JOHN D. RAYMOND, a citizen of the United States, residing at Chicago, in the county of Cook and State 5 of Illinois, have invented certain new and useful Improvements in Electric-Lighting Fixtures, of which the following is a specification.

One of the objects of this invention is to 10 produce improved means for adjusting the lamp socket with relation to the remainder of the fixture.

The invention also relates to the other 15 features of improvement hereinafter set forth.

In the accompanying drawing, Figure 1 is a fragmental vertical central sectional view of a lighting fixture embodying the 20 features of my invention. Fig. 2 is a fragmental central sectional view upon an enlarged scale.

In the drawings, 1 denotes a nipple, the upper portion of which is externally screw threaded to receive a suspending hook 2 or 25 link (not shown), or to permit of screwing said nipple into the lower end of a rigid stem (not shown). To the lower end of the nipple 1 is rigidly secured a shade-holder 3, said shade-holder being preferably provided with ventilating openings 4. The shade-holder 3 is adapted to support a shade, globe or the like removably secured in place by means of screws 3a. To minimize the extent to which dust may enter 35 the openings 4, a conical shield or guard 6 may be screwed upon the nipple 1 in position to overhang the shade-holder.

7 is the lamp socket. It is secured to the lower end of a nipple 8, said nipple being 40 exteriorly screw-threaded, and the nipple 1 being interiorly screw-threaded to receive the nipple 8. By reason of the screw-thread connection between the nipples 1 and 8, the socket 7 may be rotated to raise 45 or lower the lamp in order to bring the lamp into proper relation to the fixture and to facilitate access to the lamp socket. When the lamp socket has been adjusted to the desired position, it may be secured in place

by means of the set screw 9. As indicated 50 in Fig. 2, the set screw 9 extends substantially parallel with the adjacent portion of the guard 7 in order that the screw may be conveniently rotated by means of a screwdriver inserted upwardly beneath the 55 guard.

If desired, a bowl 10 of any suitable material, as, for example, translucent glass, may be suspended beneath the shade 5. Herein I have shown three hangers 11 attached at their lower ends to the bowl, the upper ends of the hangers being connected to the lower portion of an inverted cup or bell 12. The upper end of the bell 12 has an opening 13 therein through which the 60 nipple 8 extends, the bell resting upon a portion of the socket 7.

I claim as my invention:

1. In an electric lighting fixture, the combination of a shade-holder having means for detachably connecting a shade thereto, an internally and externally screw-threaded suspending nipple, to the lower end of which the shade-holder is attached, an externally threaded nipple in rotatable engagement with the internal threads of the first nipple, and a lamp socket connected to the lower end of the second nipple. 70

2. In an electric lighting fixture, the combination of a shade-holder, a shade detachably connected to the shade holder, an internally and externally screw-threaded suspending nipple, to the lower end of which the shade-holder is attached, an externally threaded nipple in engagement with the internal threads of the first nipple, a lamp socket connected to the lower end of the second nipple, a bell supported by the second nipple and surrounding the socket, a bowl and hangers connecting the bowl to the bell. 80

In testimony whereof, I hereunto set my hand in the presence of two witnesses.

JOHN D. RAYMOND.

In the presence of—
GEORGE L. CHINDAHL,
C. PAUL PARKER.
